UNITED STATES PATENT OFFICE.

PETER C. MERILLAT, OF WINFIELD, IOWA.

ATTACHMENT FOR ROAD SCRAPERS OR GRADERS.

Application filed December 27, 1921. Serial No. 525,078.

To all whom it may concern:

Be it known that I, PETER C. MERILLAT, a citizen of the United States, residing at Winfield, in the county of Henry and State 5 of Iowa, have invented certain new and useful Improvements in Attachments for Road Scrapers or Graders; and I do declare the following to be a full, clear, and exact description of the invention, such as 10 will enable others skilled in the art to which it appertains to make and use the same.

This invention relates to an improved attachment for use in connection with a conventional construction of road grader or 15 scraper and one object of the invention is to provide an attachment which may be put in place in connection with a conventional structure of road scraper and will provide a machine by means of which a relatively 20 wide strip of road may be kept properly graded and smooth and at the same time a gutter at the side of the road cleaned out.

Another object of the invention is to so 25 construct this attachment that it may include blades which will form auxiliary blades to the main scraping blade of the road grader and to so construct the attachment that a main carrying bar thereof may be connected with the turn-table with which 30 the main scraping blade is connected and the main scraping blade and auxiliary blades thus caused to move as a unit when the turn-table rotates.

Another object of the invention is to so 35 construct the auxiliary blades that they may be connected with the end portions of the main blade for vertical tilting movement and one of the blades permitted of horizontal swinging movement means being provided for controlling horizontal swinging 40 movement of the last mentioned auxiliary blade so that this auxiliary blade may be held at a desired angle with respect to the main blade and thus permit of cleaning out 45 of the gutter in a very efficient manner.

Another object of the invention is to provide improved means for vertically adjusting the auxiliary blades and retaining them in the adjusted position, the adjusting means 50 for each of the blades including a rocker bar pivotally mounted in a cradle for vertical movement and the cradle for the rocker bar having connection with the horizontally movable auxiliary blade being 55 mounted for swinging movement so that the cradle may swing horizontally with the

auxiliary blades and thus remain in the proper position above the blades.

Another object of the invention is to provide improved means for yieldably holding 60 the auxiliary turn-table carrying frame of the main scraper frame against downward movement thereby permitting of the extra weight being compensated for and the auxiliary frame permitted of being vertically ad- 65 justed very easily.

This invention is illustrated in the accompanying drawings, wherein:

Figure 1 is a top plan view of a grader having the improved attachment associated 70 therewith.

Figure 2 is a view showing the structure of Fig. 1 partially in side elevation and partially in section.

Figure 3 is a fragmentary sectional view 75 taken along the line 3-3 of Fig. 4 and substantially along the line 3-3 of Fig. 1.

Figure 4 is a sectional view taken along the line 4-4 of Fig. 3.

Figure 5 is a fragmentary perspective 80 view of one of the auxiliary blades.

Figure 6 is a sectional view taken along the line 6-6 of Fig. 3.

Figure 7 is a sectional view taken along the line 7-7 of Fig. 6. 85

Figure 8 is a sectional view taken along the line 8-8 of Fig. 6 or along the line 8-8 of Fig. 3.

Figure 9 is a sectional view taken along the line 9-9 of Fig. 1. 90

Figure 10 is a sectional view taken along the line 10-10 of Fig. 1.

Figure 11 is a sectional view taken along the line 11-11 of Fig. 1.

Figure 12 is a view showing a modified 95 construction in the forward end of the machine.

This device is an attachment to be used in connection with a road scraper or grader having a conventional construction. In 100 Figs. 1 and 2, the attachment has been shown in connection with a road scraper having a main frame which is indicated in general by the numeral 1 and an auxiliary frame 2. This auxiliary frame 2 is pivotally mounted at its forward end as shown at 3 for vertical movement and has its rear end portion supported by supports which are of a conventional construction and each of which in the present illustration consists of an 110 internally threaded sleeve 4 connected with the auxiliary frame and a threaded stem 5

which is journaled in a cross bar 6 of the main frame and provided at its upper end with a hand-wheel 7 so that the stem 5 may be readily rotated to lift or lower the rear end portion of the auxiliary frame and retain the auxiliary frame in the adjusted position. A turn-table 8 is rotatably carried by the auxiliary frame and the main scraping blade 9 which is the usual scraper blade provided upon road scraper is carried by this turn-table and may be placed at the desired angle with respect to the road by turning of the turn-table. All of the details of construction in connection with the main frame and auxiliary frame and turn-table have not been shown as this structure is a conventional construction and only sufficient structure has been illustrated to show the application of the attachment to the road scraper.

This attachment is to turn with the turn-table and therefore there has been provided a main carrying bar 10 which is secured upon the turn-table in front of the main blade 9 by means of cross strips 11 which extend above and below the main carrying bar and are bolted to this carrying bar and to cross strips 12 and 13 of the turn-table. This carrier bar extends beyond the turn-table and beyond the sides of the frame. At one side of the machine, there has been provided inner and outer sets of cross strips 14 and 15 which are secured above and below the carrier bar 10 in crossed relation thereto by means of bolts 16. The depending portion of the outer cross strip 14 is secured to the main blade 9 by a bolt 9' and is also secured to a depending portion 15' of the cross strip 15 by a bolt 14' as shown in Fig. 11. The lower end of the depending portion of the outer cross strip 14 is bent to provide space between this depending portion and the rear face of the main blade. The bolts 16 for securing the cross strips 14 and 15 extend upwardly as shown in Fig. 9 and carry a guide strip 17 which serves to guide swinging movement of a cradle and to prevent tilting movement of this cradle as will hereinafter be brought out. From an inspection of Fig. 9, it will be seen that the depending-end portions of the strips 14 and 15 are secured by bolts which pass through the upper portion of the blade. The auxiliary scraping blade 18 for this side of the machine has its inner end portion extending behind the end portion of the main blade and connected with the bowed portion of the depending end of the outer cross strip 14. This blade will be permitted of vertical and horizontal swinging movement so that it may be adjusted as will be hereinafter brought out. Upon the opposite side of the frame, there has been provided an outer cross strip 19 which is secured by means of a bolt 20 and pro-

vided with a depending end portion secured to the rear face of the blade 9. Inner cross strips 21, 22 and 23 are secured in crossed relation to the carrier bar with the strip 23 extending beneath the carrier bar and secured to the rear face of the main blade 9. The upper cross strips are held in spaced relation upon the securing bolts 24 and 25 and bracing strips 26 are carried by the bolt 24 and connected with the rear face of the depending portion of the strip 19. The auxiliary blade 27 upon this side of the machine is positioned in front of the blade 9 adjacent the end thereof and carries a strip 28 which is secured upon its rear face by means of fastener bolts 29 which extend through slots in the end portions of the strips 28. The main scraper blade 9 carries a bearing strip 30 which is arcuate in cross section and secured at its lower end by a fastener bolt 31 and has its upper end connected with a bracket plate 32 in which is formed a slot 33 to receive a securing bolt 34. By having the bearing strip 30 secured as shown, this strip may be positioned at the desired angle upon the blade 9 so that when the bolt 35 is put in place as shown in Fig. 6 and Fig. 8, the blade 27 will be mounted for horizontal and vertical swinging movement and therefore practically permitted of universal swinging movement. The blades 18 and 27 are to be permitted of free swinging movement in a horizontal direction and it is desired to brace these blades against rearward movement in the horizontal plane so that they may be retained at the desired angle with respect to the main blade. There has therefore been provided a sectional shaft which is carried by the main frame and provided with end portions 36 and 37 which carry sleeves 38 and 39, the sleeve 38 being rigid upon the section 36 of the shaft and the sleeve 39 being rigid upon the section 37 of this shaft and fitting loosely upon the section 36 as shown in Fig. 1. A cable 40 is wound upon the sleeve 38 and a chain 41 is wound upon the sleeve 39. The chain and the cable are carried forwardly and about pulley wheels 42 carried by a bracket 43 at the forward end of the machine and the cable 40 is then carried rearwardly and connected with an arm 44 which extends forwardly from the free end portion of the auxiliary blade 18. The chain 41 is carried rearwardly and after being passed over the pulley wheel 45 which is suspended by the chain 46 from the main frame of the machine is connected with the bracket 47 swiveled upon the free end portion of the arm 48 which extends forwardly from the free end portion of the auxiliary scraper blade 27. By having the bracket 47 provided with the vertically disposed bar 49 which is perforated as shown in Fig. 5, the end of the chain 41 may be connected with

the bracket at the desired point with respect to the arm 48. Therefore the proper pull can be exerted upon the auxiliary blade 27. When the machine is in use, the shaft 5 sections 36 and 37 may be rotated to let out upon the line and chain 40 and 41 or may be rotated to wind the chain and line or cable upon the sleeve until the auxiliary blades are in the proper position with respect to the 10 main blade 9. The latches 50 can then be brought into engagement with the ratchet wheels 51 and the sleeve will be held against rotation which would permit of further unwinding of the cable and chain and the two 15 auxiliary blades will be firmly braced and prevented from moving rearwardly out of the desired position.

In addition to having the blades held against horizontal movement beyond a desired point, it is also desired to provide means for vertically adjusting the auxiliary blades and releasably holding them in the adjusted position. In order to do so, each blade will be provided with the adjusting 25 means which will now be described. Upon each end portion of the carrier bar 10 there will be provided a cradle, these cradles being pivotally mounted at their outer ends by the bolts 20 and having their inner end portions extending for projecting between the cross strips 14 and 17 and 21 and 22. Therefore, each cradle is permitted to have swinging movement and will be guided in its swinging movement and held against vertical tilting movement. Each cradle is provided with a base 52 which is formed of channel iron. Bearing arms 53 are provided at the outer ends of the base strip and extend upwardly from the side flanges thereof 30 and a yoke or bearing 54 which is of an inverted U-shape extends upwardly from the inner end portion of the inner end of the base strip. Bracing strips 55 are provided and serve to retain the bearing strips 53 and 35 yoke 54 the proper distance apart and in a vertical position. A rocker bar 56 which is preferably formed as a hollow tube extends longitudinally of this cradle and is provided intermediate its length with a sleeve or collar 57 from which extends bearing ears 58 so that the rocker bar may be mounted for 40 vertical swinging movement as shown in Fig. 6. This rocker bar is braced by truss rods 59 which have their forward end portions passed through a head plate 60 and provided with securing nuts so that the truss rods may be placed under tension. Strips or arms 61 are connected with the outer end 45 portion of this rocker bar and extend downwardly and have their lower end portions engaged by a bolt 62 which extends through a slot 63 formed in a strip 64 which is connected with the auxiliary blade and extends above the upper edge of the auxiliary blade. 50 A spring 65 is provided about this strip 64

and engages the auxiliary blade and bolt 62 so that the auxiliary blade will be yieldably held against upward movement by this spring 65 but permitted to have upward movement against the action of the spring 70 in case the blade should strike an obstruction in the road over which it could not pass without damage to the machine if this upward movement of the blade were not provided for. In order to permit of the rocker 75 bar being swung vertically and releasably held in an adjusted position with the auxiliary blade held at the desired angle, there has been provided a threaded shaft 66 which has its lower end portion passed through a bearing strip 67 and has its upper end portion passing through the cross head of the yoke 54. An internally threaded block 68 is pivotally and slidably mounted between arms 69 as shown in Figs. 3 and 4 by means of side pins 68' which fit into slots 69' formed in the arms 69. These arms 69 extend upon opposite sides of the rear end portion of the rocker bar as shown in Figs. 3 and 4 and this block 68 is mounted upon the threaded 80 shaft 66 so that as the shaft is rotated, the block will be moved vertically upon the shaft and the rocker bar will be swung vertically to lift or lower the auxiliary blade 85 and support the auxiliary blade in the desired position. The shaft 66 extends above the yoke and carries a beveled gear 70 which is secured upon this shaft between the arms of the bearing bracket 71. This bearing bracket 71 is loosely mounted upon the upper end portion of the shaft 66 and serves to 90 rotatably mount an operating shaft 72 upon the forward end portion of which is provided a gear 73 which meshes with the gear 70. This operating shaft 72 extends rearwardly of the machine and extends through an opening formed in the upper end portion of the standard or support 74. The opening in the standard or support 74 through which the shaft 72 passes will be of sufficient size 95 to permit the shaft to have rotary movement and also to permit of sliding movement and of sufficient transverse movement to permit the cradle and rocker bar to have the desired swinging movement in a horizontal 100 plane. 105

When this machine is in use, it can be used as an ordinary road scraper with the auxiliary blades swung up out of position for engagement with the ground. When it is desired to cover a greater portion of the road with a single operation, the actuating shaft 72 will be turned by means of the hand wheel 75 and the rocker bars will be 110 swung upon their pivots to lower the auxiliary blades. If during the scraping of the road, it is desired to clean out a gutter at the side of the road, the auxiliary blade at that side of the machine will be swung 115 downwardly a sufficient extent to extend 120 125 130

down into the gutter and thus clean out the gutter while the machine is moving along the road. The auxiliary blades may be positioned as shown in Fig. 1 and held 5 in this position against further rearward movement by the chain 41 and cable 40. When in this position, the material gathered by the scraper will move along the auxiliary blade 27 to the main blade 9 and will 10 then move along this main blade 9 onto the auxiliary blade 18. When it is desired to clean out a gutter, or ditch and spread the dirt evenly over a road, the auxiliary blade 27, the main blade 9 and the auxiliary blade 15 18 can be raised or lowered and held in position so that they will clean out the side of the ditch and spread the material where wanted and build up the road to any shape desired. In fact all the material can be 20 spread before reaching the end of auxiliary blade 18 thereby cleaning the side of the ditch and shaping up the shoulder of the road all in one operation. Surplus material which reaches the end of the auxiliary blade 25 18 will be left upon the road where it can be very easily collected. If desired, the material which has been scraped toward the center of the road may be formed in piles by setting the main blade 9 so that it ex- 30 tends transversely across the machine and setting both of the auxiliary blades so that they extend forwardly. A substantially triangular shaped scraping structure will thus be provided so that the material to be re- 35 moved in wagons can be scraped into piles. After a sufficient quantity has been gathered to form one pile, the hand-wheels 7 will be turned to rotate the stems 5 and thus draw the auxiliary frame 2 upwardly a sufficient 40 distance to permit of the scraping blades passing over the pile which has been formed. The hand-wheels will then be turned in the opposite direction to again bring the scraping blades into the operative position. 45 When the auxiliary blades and operating structure are applied to the auxiliary frame of the scraper, they add extra weight which would make it somewhat difficult to raise the auxiliary frame and therefore there has been 50 provided cables 76 which are connected with the auxiliary frame and then carried upwardly and passed over pulley wheels 77 carried by a shaft 78. The cables are then extended forwardly and connected with 55 plungers 79 which are slidably mounted in bearing brackets 80 and yieldably held against rearward sliding movement by means of springs 81. These springs will thus serve to yieldably retain the auxiliary frame 60 against downward movement and assist materially in the lifting of the auxiliary frame. There has thus been provided an attachment which can be readily connected with a conventional structure of road scraper. 65 In some cases, it has been found that it is

better to have the bracket 43 extend forwardly of the front axle instead of rearwardly therefrom as shown in Fig. 1. The bracket can then be arranged as shown in Fig. 12 with the chain 41 extending in front of the front wheel and directly connected to the arm 48 instead of extending beneath the frame of the machine and after engaging the guide pulley 45 have its end connected with the bracket 47. 75

I claim:

1. The combination with a road scraper including a frame, a turn-table, and a road scraping blade carried thereby, of auxiliary scraping blades connected with the end portions of the first mentioned scraping blade, and means connected with one of the auxiliary blades for bracing the blades and table against turning in one direction and for turning the blades and table in an opposite direction to adjust the angular position of the blades. 80

2. The combination with a road scraper including a frame, a turn-table, and a road scraping blade carried thereby, of auxiliary scraping blades connected with the end portions of the first mentioned scraping blade, a cable connected with one of said auxiliary blades, and means for drawing upon the line to swing the turn-table and position the blades at a desired angle and brace the blades against movement out of the desired position. 90

3. The combination with a road scraper including a frame, a turn-table, and a road scraping blade carried thereby, of auxiliary scraping blades connected with the end portions of the first mentioned scraping blade, both of said auxiliary blades being mounted for vertical swinging movement and one of the auxiliary blades being mounted for horizontal swinging movement, means for horizontally adjusting the last mentioned auxiliary blade, means connected with the other auxiliary blade for bracing the blades and turn-table against turning as a unit in one direction, and means for vertically adjusting the auxiliary blades. 100

4. The combination with a road scraper including a frame, a turn-table, and a road scraping blade carried thereby, of auxiliary scraping blades connected with the end portions of the first mentioned scraping blade, a cable connected with one of said auxiliary blades, a drum carried by said frame, guide means adjacent the forward end of said frame, the cable being wound upon said drum and carried forwardly and about the guide means and then rearwardly and connected with the outer end portion of the auxiliary blade to brace the blades and turn-table against turning as a unit in one direction. 115

5. The combination with a road scraper including a frame, a turn-table, and a road 120

scraping blade carried thereby, of auxiliary scraping blades connected with the end portions of the first mentioned scraping blade, both of said auxiliary blades being mounted 5 for vertical swinging movement and one of the auxiliary blades being mounted for horizontal swinging movement, means for vertically adjusting said auxiliary blades, a winding shaft carried by the frame and 10 having independently rotatable end portions, guide means adjacent the forward end of the frame, an arm extending from the auxiliary blade having horizontal movement, and cables wound upon the end portions 15 of the drum and carried forwardly and engaged with the guide means, one cable being connected with the arm to brace the horizontally swinging blade against rearward swinging movement and the other 20 cable being connected with the other auxiliary blade to brace the blades and turn-table against turning as a unit in one direction.

6. The combination with a road scraper 25 including a frame, a turn-table and a main scraper blade carried by the turn-table, of an auxiliary blade connected with the main blade for vertical swinging movement and extending beyond the end of the main 30 blade, a rocker bar pivotally mounted above the auxiliary blade, an arm depending from the outer end of said bar and slidably connected with said auxiliary blade, resilient means yieldably holding the auxiliary blade 35 against vertical movement independent of said arm, and means for rocking the rocker bar to vertically adjust the auxiliary blade.

7. The combination with a road scraper including a frame, a turn-table and a main 40 scraper blade carried by the turn-table, of an auxiliary blade connected with the main blade for vertical swinging movement and horizontal swinging movement, means for controlling horizontal swinging of the auxiliary 45 blade, a cradle pivotally mounted above said main blade for horizontal movement, a rocker bar pivotally carried by the cradle for vertical swinging movement and extending longitudinally of the cradle and 50 having its outer end portion connected with the auxiliary blade, and means for controlling vertical movement of the rocker bar.

8. The structure of claim 7 having the means for controlling horizontal swinging of the auxiliary blade consisting of an arm extending forwardly from the free end portion of the auxiliary blade, a drum carried by said frame, a guide adjacent the forward end of the frame, a bracket swiveled upon the end of the arm for horizontal movement, and a cable wound upon said drum and extended forwardly about the guide and connected with said bracket. 55

9. The structure of claim 7 having the cradle provided with a head extension at 60 its inner end and strips engaging the head extension to guide horizontal swinging movement of the cradle and hold the cradle against vertical tilting. 65

10. The structure of claim 7, and means 70 for bracing the cradle against vertical tilting movement.

11. The combination with a road scraper including a frame, a turn-table, a cross bar carried by the turn-table, and a main scraper 75 blade carried by the cross bar, of an auxiliary scraper blade connected with the main blade for vertical and horizontal swinging movement, a cradle pivotally connected with the cross bar for horizontal swinging 80 movement, a rocker bar extending longitudinally in the cradle and pivotally mounted for vertical movement and having its outer end portion connected with the auxiliary blade, an internally threaded block at the 85 inner end of said rocker bar, a threaded shaft journaled vertically in the inner end portion of said cradle and passing through the block, means for rotating the threaded shaft to impart rocking movement to said 90 rocker shaft, and means for controlling horizontal swinging movement of the auxiliary blade and cradle. 95

12. The structure of claim 11 having the threaded shaft extending above the cradle, 100 a bearing bracket loosely mounted upon the extended end portion of the threaded shaft, an operating shaft journaled in the bearing bracket, and intermeshing gears carried by the operating shaft and threaded shaft.

In testimony whereof I have hereunto set my hand.

PETER C. MERILLAT.
